UNITED STATES PATENT OFFICE.

JAMES TAYLOR, OF ST. PAUL, MINNESOTA.

MEANS FOR ERECTING CONCRETE STRUCTURES.

953,732.

Specification of Letters Patent. Patented Apr. 5, 1910.

Application filed December 18, 1907. Serial No. 403,592.

To all whom it may concern:

Be it known that I, JAMES TAYLOR, a subject of the King of Great Britain and Ireland, residing at St. Paul, in the county of Ramsey and State of Minnesota; have invented a new and useful Improvement in Means for Erecting Concrete Structures, of which the following is a specification:

My invention relates to improvements in means for erecting concrete structures.

It has for its object the simplification of, and economy in, the construction of such structures to the end that less skilled labor may be required and to make possible and convenient the repeated use of the forms and frames employed in the erection of buildings of the class described.

In the drawings Figure 1 is a building in process of construction with my apparatus in position ready for concrete filling; Fig. 2 is a horizontal plan view of my frame and uprights locked in position to receive the concrete; Fig. 3 is a vertical plan of the same; Fig. 4 is a section of Fig. 3 taken on the line X—X; Fig. 5 is a section of one of the uprights taken on the line A—A; Fig. 6 is a vertical section of the frames taken on the line Z—Z of Fig. 7, showing cores in place for molding a hollow wall; and Fig. 7 is a plan view of the construction shown in Fig. 6.

My apparatus comprises frames A, uprights B, frame bolts C, frame tubes D, and frame locks E, and also, where it is desired to produce a double wall having a dead air space, cores F and anchors G. The frames A consist preferably of timbers lined and reinforced with metal, and the uprights B of metal or timber reinforced with metal; the uprights for the corners being L-shaped and those for the sides T-shaped in horizontal cross section. The uprights are placed in perpendicular position on either side of the concrete wall to be erected and are of sufficient length to permit the repeated re-adjustment upon them of the frames A at successively higher points as the construction of a building progresses. The frames are secured together in pairs by means of the bolts C and tubes D, the latter being of a length equal to the thickness of the wall to be erected, and extend between the inner surfaces of the outer and inner frames.

The bolts C pass through the perforations 1 in the frames and uprights and through the openings in the tubes D, which are ar-

ranged to register with the perforations. The bolts C when inserted in the frames and tubes are held firmly in position by means of the nuts 3. The same arrangement of tubes and bolts connects and holds rigidly parallel the pairs of uprights B. It will thus be seen that the frames A and uprights B on the inner and outer sides of the proposed wall are held apart and parallel to each other by the tubes D and are bonded together by means of the bolts C secured by the nuts 3. The diameter of the tubes is greater than that of the perforations 1 and to obtain greater durability in the repeated use and re-adjustment of the frames, washers or plates 4 may be countersunk in the frames to form bearing surfaces for the ends of the tubes D and for the nuts 3.

The frames are locked to the uprights B by means of the locks E which consist of cam levers provided with pins 5 adapted to pivot in the eyes 6 in the uprights, and, having their bearing surfaces 7 against the cut-away ends 8 of the frames so that the frames may be adjusted and locked to the uprights at any desired height by turning the lever about the pivot point formed by the pin 5 in the eye 6. If it is desired to produce a hollow wall cores F (Figs. 6 and 7) of any desired form and thickness may be inserted between the frames and tubes. Cores 15 may also be placed across the space between the sides for anchors G which serve to hold the sides of the wall together. The cores F as shown have metal face plates 11 secured thereto by screws 12 and are sectional, the parts thereof being held normally in place between shoulders 13 on the anchors G and anchor cores 15. A vertical key 16 between the sections of each core F serves to hold the sections tightly between the shoulders and when drawn out permits the sections to be removed. After the anchor cores are lifted out, the anchors can be inserted in the molds 11 by them in the concrete.

In operation, the frames are filled with concrete, which is allowed to set. After the concrete sets the frames may be raised and again bolted and locked to the uprights immediately above the completed portion of the wall. In the case of a hollow wall the cores are removed and again placed within the frames, and the steps hereinbefore described are repeated until the top of the uprights is reached. The uprights are then raised and

plumbed as before, this operation being facilitated by bolting the lower ends of the uprights into the upper tubes D or holes left by them in the wall already constructed.

5 As the construction progresses the tubes D may be knocked out of the walls while concrete is green, and the apertures left in the wall may be filled with concrete. The tube holes in the wall provide means for securing brackets in place for supporting scaffolding, and may be used for ties for brick facing on the wall when desired.

Having described my invention, what I claim as new and desire to protect by Letters Patent, is:-

1. In a device of the class described, inner and outer frames, cores provided with lateral anchors and a vertical key, means for holding the frames and cores in rigid, paral-

lel relation to each other and uprights provided with locks adapted to support the frames and permit them to be moved step by step upward.

2. In a device of the class described, the combination of mold frames, cores and uprights, tubes passing through the cores and of a length equal to the thickness of the wall to be erected, bolts extending through the frames, uprights and tubes, and locks for the frames carried by the uprights.

In testimony whereof I have signed my name to this specification in the presence of two subscribing witnesses.

JAMES TAYLOR.
